[57] CLAIM

The ornamental design for an electrical box mount, as shown and described.

DESCRIPTION

FIG. 1 is a perspective view of the electrical box mount showing my new design with one of the mounting brackets separated from the box. The broken lines throughout the drawing figures represent typical knockouts which provide access for electrical cables and are intended as claimed subject matter;

FIG. 2 is a front elevational view of the electrical box mount showing my new design in the assembled condition;

FIG. 3 is a rear elevational view thereof;

FIG. 4 is a side elevational view thereof;

FIG. 5 is a side elevational view thereof; and,

FIG. 6 is a top plan view thereof, the bottom view being a mirror image of the top view shown in FIG. 6.
